Primary Examiner — T Chase Nelson*Assistant Examiner* — Sydney Margaret Parsley(74) *Attorney, Agent, or Firm* — Dicke, Billig & Czaja, PLLC**CLAIM**

The ornamental design for a landscape block, as shown and described.

DESCRIPTION

FIG. 1 is a perspective view of the landscape block.

FIG. 2 is a top view thereof.

FIG. 3 is a bottom view thereof.

FIG. 4 is a right side view thereof.

FIG. 5 is a left side view thereof.

FIG. 6 is a front view thereof; and,

FIG. 7 is a rear view thereof.

The surface portions shown in broken lines form no part of the claimed design.
